U.S. PATENT DOCUMENTS

D522,022 S * 5/2006 Carlin et al. D15/5

FIG. 1 is a perspective view of an embodiment of an exhaust gas recirculation module for a diesel engine, showing the new design.

FIG. 2 is a side view of the embodiment of FIG. 1.

FIG. 3 is another side view of the embodiment of FIG. 1.

FIG. 4 is a front side view of the embodiment of FIG. 1.

FIG. 5 is a rear side view of the embodiment of FIG. 1.

FIG. 6 is a top view of the embodiment of FIG. 1; and,

FIG. 7 is a bottom view of the embodiment of FIG. 1.

The broken lines are for illustrative purposes only, and form no part of the claimed design.
